United States Patent Office.

ALFRED B. SHEAFFER, OF EPHRATA, PENNSYLVANIA.

Letters Patent No. 78,240, dated May 26, 1868.

IMPROVED MAIN-BOLT OR GOOSE-NECK STAY ON CARRIAGES.

The Schedule referred to in these Letters Patent and making part of the same.

TO ALL WHOM IT MAY CONCERN:

Be it known that I, ALFRED B. SHEAFFER, of Ephrata, in the county of Lancaster, and State of Pennsylvania, have made certain Improvements on the Main-Bolt or Goose-Neck Stay on Carriages, in connection with the so-called fifth-wheel; and I do hereby declare that the following is a full and exact description thereof, reference being had to the accompanying drawings, making a part of this specification, in which—

Figure 1 is a perspective view of the stay.

Figure 2, the bolt and socket-nut.

Figure 3 illustrates its application, showing the elliptic spring, head-block, fifth-wheel, and axle, with the clips and stays in place.

The nature of my invention consists in providing a pocket or socket under the fifth-wheel and around the main bolt, for the introduction of gum-elastic to act as a follower, and prevent rattling, said sockets being a part of the main-bolt brace and the nut that holds the bolt.

To enable others skilled in the art to make and use my invention, it is only necessary to say that the open curve A, fig. 1, for the passage of the wheel or circular slides I, is deepened, forming a thickened curve, B, out of which is cut or forged a square or oblong socket, a, for the reception of a piece of India rubber or gum-elastic, G, which more than fills the socket. An iron or steel plate, P, is made to fit, and laid over the gum within the socket. The wheel I, be it single or double, fills the space in the usual manner, pressing upon the plate and gum which it covers. The action of the gum is such as to prevent rattling or becoming loose by wear.

The bolt, fig. 2, (that holds the forward end, e, of the goose-neck or main stay and wheel-guide,) has a nut, with a prolongation, L, a part of the nut N, provided with a widened socket for a ring of gum-elastic, M, over which a washer, W, is also inserted, so as to prevent rattling and keep the parts in close connection, as friction, in time, loosens the same.

I am aware that iron rings are used as washers with a ring of gum-elastic; but I am not aware that a screw-burr or nut, with a socket, was ever before known or used.

I am also aware that patent, 60,634, December 18, 1866, claims a safety-clip, between which the fifth-wheel plays in the recesses, having a yielding pressure. This is an independent thing, and is secured in a special manner, and forms no part of the main-bolt stay. I do not claim a safety-clip attached separately. My socket-opening is a part of and forged with the main-bolt or goose-neck stay, as is the socket in the nut a part of the same, and not an extra piece.

What I claim as my invention, and desire to secure by Letters Patent, is—

The socket a, in the enlarged curve B of the main-bolt stay A, when made substantially in the manner and for the purpose specified.

ALFRED B. SHEAFFER.
